US00D359108S

United States Patent [19]

Vestergaard

[11] Patent Number: Des. 359,108

[45] Date of Patent: ** Jun. 6, 1995

**[54] THERMOSTATIC EXPANSION VALVE FOR
REFRIGERATING PLANTS****[75] Inventor:** Anders Vestergaard, Sydals,
Denmark**[73] Assignee:** Danfoss A/S, Nordborg, Denmark**[**] Term:** 14 Years**[21] Appl. No.:** 19,128**[22] Filed:** Feb. 23, 1994**[30] Foreign Application Priority Data**

Aug. 23, 1993 [DE] Germany M9306710.0

[52] U.S. Cl. D23/233

Primary Examiner—A. Hugo Word*Assistant Examiner*—E. Watterson*Attorney, Agent, or Firm*—Lee, Mann, Smith,
McWilliams, Sweeney & Ohlson**[57] CLAIM**The ornamental design for a thermostatic expansion
valve for refrigerating plants, as shown and described.**DESCRIPTION**FIG. 1 is a perspective view of a thermostatic expansion
valve for refrigerating plants according to my invention;

FIG. 2 is a perspective view opposite to that of FIG. 1;

FIG. 3 is a top plan view thereof;

FIG. 4 is a bottom plan view thereof;

FIG. 5 is a front elevational view thereof;

FIG. 6 is a rear elevational view thereof;

FIG. 7 is a side elevational view thereof;

FIG. 8 is a side elevational view thereof opposite to
FIG. 7; and,FIG. 9 is a perspective view of an alternative embodi-
ment of my invention.FIGURE 1
